SELECTIVE TELEGRAPH SYSTEM.

1,078,899.

Specification of Letters Patent. Patented Nov. 18, 1913.

Application filed January 6, 1910. Serial No. 538,616.

To all whom it may concern:

Be it known that I, ELMER A. BURLINGAME, a citizen of the United States, residing at Boston, county of Suffolk, Commonwealth of Massachusetts, have invented certain new and useful Improvements in Selective Telegraph Systems, of which the following is a specification.

This invention relates to a system for securing selection through an electric circuit, and particularly to the selection of one or more of a number of local circuits at a distance over a single wire. The local circuit selected may be employed to make a still further selection or to start or operate or cut off any mechanisms or devices or to do anything capable of control by a local circuit.

In order to simplify the discussion of my invention this application will treat my invention with particular relation to the selection of operating parts of mechanisms intended to transmit messages, and as a specific illustration of my invention I shall discuss and discuss the same with relation to the transmission of characteristic impulses for the operation of mechanisms at a distance intended to produce a perforated tape capable of operating a mechanically operated typewriter or similar printing device. In the operation of such systems heretofore difficulty and delay have been experienced both in the selective systems and in the employment of the different agencies composing the same. Considerable delay has been involved on account of the difference of speed at which the character impulse selection, the transmission, and the receiving or printing mechanisms could be operated. For instance, where a tape has been prepared with characteristic perforations for use in a local transmitting device the operation of the receiving machine has not been sufficiently rapid to receive the entire intelligence transmitted.

One of the features of my present invention, therefore, is a system in which the characteristic selections are made and transmitted by series of characteristic impulses to a distant station at which the tape is perforated. By my system I am enabled to make one receiving machine take care of

the tapes of at least two transmission systems.

Various features of the system and the construction and arrangement of the parts will be more fully described in the specification which follows. In the specification, as explained above, by a system involving my invention I have set forth an illustrative embodiment thereof, and this I have illustrated in the drawings which form a part of the specification.

Throughout specification and drawings like reference numerals are employed to indicate corresponding parts throughout, and in the drawings: Figure 1 is a diagrammatic view showing a selective transmission system, Fig. 2 a diagrammatic illustration of a receiving system for the same, Fig. 3 a detail of the line closer contacts, Fig. 4 a detail of the switch contacts, Fig. 5 a detail view of a portion of the controlling mechanisms of the actuating system for the line closers, and Fig. 6 a detail of the tape feed.

1 is a generator having a line 2 connected to its positive brush and a line 3 connected to its negative brush.

4 is a line connected with a resistance 5 and in circuit with the negative brush. 80

6 and 7, 8 and 9 and 10 and 11 are pairs of line closers, each of said line closers consisting of a three blade switch. The closer 6 consists of a central blade 6¹, a lower blade 6² and an upper blade 6³. Each of the other line closers 7, 8, 9, 10 and 11 have similarly arranged middle, lower and upper blades. The lower blades 6² and 7² of the pair 6, 7; 8² and 9² of the pair 8, 9; 10² and 11² of the pair 10, 11 are connected. 90 The middle blades 7¹, 8¹ of the switches 7 and 8 and 9¹, 10¹ of the switches 9, 10 are also connected and the blade 6¹ of the switch 6 is connected with the north line 12, while the blade 11¹ of the switch 11 is connected 95 with the south line 13.

The upper blades 6³, 7³, 8³, 9³, 10³ and 11³ are connected as follows: The upper blade 6³ of the switch 6 is connected to a line 14, while the upper blade 7³ of the switch 7 is connected to a line 15. In like manner the upper blade 8³ of the switch 8 is connected to a line 16 similar to 14, while the upper blade 9³ of the switch 9 is connected to a line 17,

similar to the line 15, and the upper blade 10³ of the switch 10 is connected to a line 18, similar to 14 and 16, while the upper blade 11³ of the switch 11 is connected to a line 19, similar to lines 15 and 17.

- 5 21 to 32, inclusive are arms of twelve switches, each switch consisting of two pairs of contacting blades, that is to say, the blade 21 has a corresponding contact member 21¹.
 10 The blade 21, by means of an insulating rod 21⁴, further operates a blade 41 which has a corresponding contact member 41¹. The remaining switches, 22 to 32, inclusive, have similar insulating rods (not shown). In the
 15 same way the blade 22 has a corresponding contact member 22¹ and operates a blade 42 which has a corresponding contact member 42¹. These double switches are arranged in groups of four, that is to say, the switches
 20 of which the blades 21, 22, 23 and 24 are members constitute one group; those switches of which the blades 25 to 28, inclusive, are members constitute a second group; while those switches of which the
 25 blades 29 to 32 are members constitute a third group.

250 to 261, inclusive, are twelve operating bars, each having a hook for engagement with the first named arm of the double
 30 switch member. For instance, the bar 250 has a hook 250¹ which engages the arm 22 of the second double switch.

270 is one of a plurality of operating keys. There will be the same number of
 35 these keys as there are double combinations in the selecting device. For instance, in the system shown, there might be sixty-four keys, or any part of sixty-four, according to the number of letters, numbers, or other
 40 characters desired to be transmitted.

The double switches are connected with the lines 2, 3, 4, 14, 15, 16, 17, 18, and 19 in the following manner: Each of the groups of four switches, to wit: those represented by the levers 21 to 24, inclusive; 25 to 28, inclusive; and 29 to 32, inclusive; are connected to the lines 14 and 15; 16 and 17; and 18 and 19, respectively. That is to say, the switches of which the levers 21 to 24
 45 are a part are connected to the lines 14 and 15 which lead to the line closers 6 and 7, while a second group is connected to the lines 16 and 17, connected with the line closers 8 and 9, while the third group is
 50 connected by the lines 18 and 19 to the line closers 10 and 11. In each group the four double switches are connected as follows: I will refer to the first group on the left of Fig. 1 as illustrative of the connection of
 55 the other two groups. In the first switch, of which the levers 21 to 41 are members, the lever 21 is connected to the line 15 while the lever 41 is connected to the line 14. In the next switch the lever 22 is connected to
 60 the line 14 while the lever 42 is connected

to the line 15. It will thus be seen that in each group of four the connection of the upper and lower levers of each switch to the lines 14 and 15 is reversed alternately. It is further to be noted that the contacts 41¹ and 42¹ are connected with the line 3 which is the negative line, while the contacts 21¹, 22¹ are connected with line 2 which is the positive line. This same connection applies in the other two groups of four double switches, each having their upper and lower levers 25, 45, 26, 46, 27, 47, 28, 48, similarly connected alternately to one or the other of the lines 16 and 17 and their contacts 45¹, 46¹, 47¹, and 48¹ connected in alternate pairs 70 to apply the line 2 and the line 3. We have, therefore, twelve double switches divided into three groups of four each, half of each group having a connection with one of a pair of oppositely connected line closers and the other half with the other of said oppositely connected line closers, these groups being arranged alternately with one contact of the double switches (arranged in pairs) connected to either the negative line 3 or 80 the negative resistance line 4. There is, therefore, possible through the selection of one of the group of four switches with their oppositely connected line closers a strong 85 or a weak current which may be delivered 90 to the line in either the positive or the negative direction. These groups of four double switches with their pairs of oppositely connected line closers have been so far treated independently but it is to be borne in mind 95 that the generator connections run through all three groups in symmetrical series. This is for the reason that in the present example, used for illustration, I am contemplating the transmission of a treble impulse. It will 100 be noted, therefore, that the positive line 2 is connected with each one of the lower contacts 21¹, 22¹, etc., to 32¹, inclusive, while the negative line 3 connects with the upper contacts in pairs, to wit: with 41¹, 42¹, 45¹, 46¹, 49¹, 50¹, while the negative resistance line 4 connects with the upper contacts in pairs 43¹, 44¹, 47¹, 48¹, 51¹, 52¹. The connection of the upper and lower switch arms, represented by the series 21 and 41 has been 105 explained and it now remains to describe the line closing system which sends to the line characteristic treble impulses selected through a series of switches.

As was early noted, the switches indicated 120 by the general numbers 6, 7; 8, 9; and 10, 11, constitute three pairs of line closers, one each of said pairs being connected to what we will call the north line 12 and the other to the south line 13. It will be understood 125 that in an intermediate station the lines 12 and 13 might go in opposite directions, while at a terminal station one line or the other would be grounded.

Referring to Fig. 3 for a minute, it will be 130

seen that there are three arms which I have numbered 6¹, 6², and 6³, to correspond with the first line closer indicated at the left of Fig. 1. It is to be borne in mind that each one of the six line closers which constitute the three pairs is the same in structure. The arm 6³ has a projection 60 which contacts with a cam 64 in which there is a depression 65. 66 is a depending undeturned foot with a contact point 63, (see Fig. 3,) adapted to engage when the arm 6³ rises in the depression 65 with a contact point 63¹ on the arm 6¹. The arm 6¹ has a second contact point 61 adapted to be held in contact with a point 62 on the arm 6². The cam 64 mentioned is one of six cams 64, 74, 84, 94, 104 and 114. These cams are all fixed on a shaft 120 driven by a pulley 130 which may be connected by a pulley 140 to any source of power. The six cams, as has been stated, are divided into three pairs of like cams, that is, the cams 64 and 74 have similarly disposed depressions 65 and 75; the cams 84 and 94 have similar depressions 85 and 95, but set at 120° from the depressions 65 and 75; and the cams 104 and 114 have depressions 105 and 115 set 120° from the depressions previously mentioned. It will thus be seen that upon the rotation of the shaft 120 the pairs of cams will actuate the pairs of line closers at regular intervals, thus making a possibility of connection of the north and south lines successively with each of the three groups of four double switches. Again referring to the connection of the line closers, it is to be borne in mind that the lower contacts 6² and 7² are connected and the lower contacts 8² and 9² are similarly connected as a pair and the lower contacts 10² and 11² are coupled as a pair. The middle switch 6¹ of the first line closer 6 is connected to the north line and the last middle contact 11¹ of the line closer 11 is connected with the south line 13. The four intervening middle contacts 7¹, 8¹, 9¹, and 10¹ are connected together as pairs, namely, 7¹, 8¹, and 9¹, 10¹ so that the north and south lines 12 and 13 are capable of a potential series through the middle and lower contacts of the line closers. The upper contacts 6³ to 11³, inclusive, as has been stated, are connected as follows: 6³ to line 14; 7³ to line 15; 8³ to the line 16; 9³ to the line 17; 10³ to the line 18; 11³ to the line 19. These upper contacts through the points 63 and 63¹, referring to Fig. 3, may, therefore, introduce in the circuit of the lines 12 and 13 a selected characteristic impulse either positive strong, negative strong or positive weak or negative weak, according as the selection has been made, by the members 21, 22, 23 or 24, according to which was operated by the key 70. The pairs 8 and 9 and 10 and 11 are successively operated in the order 65 of the presentation of the recesses 85 and 95

and 105 and 115 to the projections 80 and 90 and 100 and 110 by the rotation of the shaft 120. The quality of impulse sent by the pairs 8 and 9 and 10 and 11 is determined by the members 25, 26, 27 or 28 and 29, 30, 31 or 32, according to which has been operated through its mechanical connection to the key 270. The switches 6, 8 and 10 always connect to line 12 and switches 7, 9 and 11 to line 13. 75

Referring now to Fig. 2, which relates to the receiving end of the system, we have the north line 12 and the south line 13. In series with these two lines are three relays which are as follows: 150, 160, 170. These we will consider respectively as a strong relay, a weak relay and a polarized relay. 151 is a switch arm operated by the relay 150 making and breaking contact with points 152. The arm 151 and the points 152 form the terminals of a circuit 153 in which is a battery 154 and a magnet 155. The magnet 155 has an armature 156 normally held away by a spring 157 and operating by suitable connection a punch 158. 85 A similar switch with circuit, battery, magnet, armature, spring and punch are provided for the weak relay 160 and the polarized relay 170. These switches, circuits, etc., are similar and are correspondingly numbered from 161 to 168 and 171 and 178 to conform to the numbering of those parts described in connection with the strong relay 150. The weak relay, however, has connected to its armature 166 one end of a circuit 183 in which there is a battery 184 a magnet 185 and a contact 182 which is so disposed as to be met by the armature 166 of the magnet of 165 in the weak relay system. The magnet 185 operates an armature 186 held up by a spring 187 operatively connected with a pawl hook 188 adapted to engage the ratchet wheel 190 which turns a roll 191 provided at its periphery with pins 192. These pins are spaced apart an angle equal to the teeth of the ratchet 190 and, therefore, are adapted to engage perforations successively formed in a tape 200 as it is drawn past the ends of the punches 158, 168 and 178. 201 is a die plate having 115 openings 202 adjacent to the ends of the punches 158, 168 and 178 so that the punches may cut perforations in the paper strip 200 as it passes in front of the die plate 201. 120

Referring again to Fig. 1, it will be understood that the bars 250 to 261, inclusive, are notched according to a selective system so that each of the operating keys of which only one, 270, is shown, will select a certain combination of bars which it will depress as it is itself depressed. This construction of slotted bars co-operating with a system of keys to produce a selection is well known and any one of the well known systems may be used. For instance, that sys- 130

tem shown in Letters Patent No. 121,601 of Thomas A. Edison might be employed and reference is made to said patent in order to simplify the description of my present system. Inasmuch as I contemplate the employment of a treble impulse, my present system would employ the selection of three bars on each depression of the key, as shown in the drawings, each bar having a hook, as shown in 250¹, 251¹, or 252¹, engaging one of the four operating levers of the three groups. In addition to the bars 250 to 261 there is another bar B (see Fig. 5) which has no notches cut in it for selection, but is operated by every key depressed, such as the key 270. On the shaft 120 are two cams, C and D, also a member E which is keyed to the shaft and has a recess E'. A member F is mounted on the shaft in such a way that it can be moved along the shaft within the limits of the space between member E and member G. Member G has a pin G' whose inner end projects into a groove which runs around the shaft 120, thus allowing member G to revolve while the shaft 120 is stationary, and by means of pin G' is kept from moving longitudinally on the shaft. The face of G, next to F, has teeth, G'' and the face of member F, next to G, has teeth, F'', which will mesh with G''. The teeth are formed like ratchet teeth, and the pair of members, F and G, constitute a clutch which is thrown into operation by a movement of member H in the direction of the arrow. Member F has a projection F' of such length that it never leaves the slot E' in its longitudinal motion of the shaft. The pulley 130 is mounted on the member G and is driven constantly through the belt 140. When the key 270 is depressed through the link I the bell crank J and link K the member H is pushed in the direction of the arrow, closing the clutch FG and causing the shaft 120 to rotate with the pulley 130. When the rotation begins the cam D causes the member L to press against the member H in the same manner that the member K did. Just before the completion of rotation the cam C, by means of the projection B', forces B back to normal position, whether or not the finger is still on the key. B must be restored to its former position before the complete revolution of the shaft, in order that H may open the clutch as soon as roller L' falls into the recess on cam D. It will be seen that the shaft 120 will make one revolution for every depression of the key 270, and will stop always in the same position, namely, with roller L', in the depression of cam D.

In the operation of my system, therefore, we will suppose that a key, such as 270, is depressed by the operator, selecting bars 250, 251, and 253 and operating the switch arms 22, 27 and 32. We will suppose that

the rotation of the cams is at a phase such that the cams 104 and 114 have their notches 105 and 115 opposite the projections at the end of the upper members 10³ and 11³. This permits these members to rise and closes the contacts on those members which correspond with the contacts 63 and 63¹ as shown in Fig. 3, breaking the contacts which correspond to those numbered 61 and 62 in Fig. 3. With the parts thus set a current from the generator will pass from the positive brush, through the line 2, until it reaches the lower contact 32¹, passing through the member 32, up through the line 18, through the member 10³, through the contacts above noted to the member 10¹. Here it passes out through the series formed by the normal contact of the lower member with a middle member of the line closers so that it connects with the north line 12 through 6¹, 6², 7², 7¹, 8¹, 8², 9², 9¹. At the same time the contact 52 has been brought against the contact 52¹. This closes the circuit from the negative brush of the generator, through the resistance 5 and the line 4 connecting through 52 and 52¹ with the line 19 which goes to the upper member 11³ and through the middle member 11¹ to the south line 13. There will be, therefore, sent to south line a weak current of negative phase. This, of course, has been instantaneous on account of the rotation of the cams and as soon as the contact has been made and broken the second set of cams 84 and 94 have become operative to work the line closers 8 and 9. The key is still depressed and the currents will pass as follows: from the positive brush of the generator, through the line 2 to the contact 27¹, through the arm 27, and line 17, the line closer 9, through the arm 9¹, across to the arm 10¹, through the arm 10² (which is now closed as the cam depression has passed), through the contact 11², through the middle arm 11¹ to the south line 13, but it is to be noted that the south line 13 is now connected to the positive brush of the generator. In the meantime the negative brush of the generator again through the resistance 5 is connected by the line 4 to the contact 47¹ which is closed on the arm 47 and hence connects with the line 16 to the line closer 8, the current passing through the member 8³ through 8¹, to 7¹, 7², 6², 6¹, and so to the north line 12. Thus the north line is connected this time with the negative brush of the generator. Thus this second impulse is sent to line 12 as a weak negative current to the north line. As soon as the cams have removed the depression from the second group of line closers the third pair of cams 64, 74 have brought their depression opposite the extensions on the lines 6³, and 7³, and a third pair of line closers is in operation. In this instance a current passes from 12¹

the opposite or positive brush of the generator through the line 2, until it reaches the lower contact member 22¹ from which it passes to the member 22 to the line 14, to 5 the upper member 6³ of the line closer 6, through the middle member 6¹ to the north line. From the negative brush of the generator a connection is made through the line 3 to the contact 42¹, through the member 42 to the line 15, and so to the upper member 10 7³ of the line closer 7 through the member 7¹ and successively through the middle and lower members of the other line closers which are now in contact, to wit: through 15 8², 9², 9¹, 10¹, 10², 11², 11¹, and so to the south line 13 which is thus connected to the negative brush direct and not through resistance. There is, therefore, sent to north line a strong positive impulse. There have, 20 therefore, been placed on the north line in rapid succession a positive weak impulse, a negative weak impulse, and a positive strong impulse. These impulses are received at the opposite end of the line as follows:

25 The first impulse, being weak, and positive, is capable only of actuating the weak relay 160. This closes the switch 161, actuates the magnet 165, operating the perforating punch 168. There is, therefore, punched 30 in the tape a single hole in the center of the tape. Upon the relaxation of the relay at the end of the impulse the parts return, and the hook pawl 188 which has been advanced by the magnet 185 at the operation of the 35 armature 166 advances the ratchet wheel 190 and rolls the tape 200 on the roll 191. The pins 192 engage the previously punched holes centrally of the tape to evenly move the tape past the plate 201.

40 The second impulse, as has been explained, is a weak negative impulse. This actuates the weak relay 160 as before and the polarized relay 170 produces a similar actuation of the parts as before, but in addition causes 45 the magnet 175 to work the armature 176 and move the punch 178 so that two perforations are made in the tape, one centrally as before represented by the weak impulse, and one at one side thereof, represented by the negative impulse.

50 The third impulse is positive and strong. Thus, it will be seen it is enabled not only to work a weak relay 160 but a strong relay 150 and thus to actuate the magnets 165 and 55 155, thus producing in the tape a central aperture corresponding to the weak relay and on one side of it an aperture corresponding to the strong relay. This aperture produced on the punch of the strong 60 relay is on the opposite side from that produced by the punch 178 of the polarized relay. The tape will, therefore, have formed in it a series of perforations of from one to three holes abreast which in groups of three 65 placed longitudinally of the tape represent

a certain character. There are obviously sixty-four possible combinations in these groups and the tape may, therefore, be passed through a receiving machine adapted to interpret in characters the character which was originally transmitted through the characteristic impulse and received on the tape in characteristic perforations. Any type of receiving machine for the interpretation of the perforated tape may be employed.

70 My invention is, of course, capable of various operations, constructions, arrangements and wiring and all such modifications are claimed as within the limits of my invention if within the terms of the claims hereunto annexed.

75 What I, therefore, claim and desire to secure by Letters Patent is:—

80 1. In a selective system a north and south line, a source of electrical energy for said lines, a pair of lines connected to opposite terminals of said source of energy, a third line from said source of energy, a resistance in said third line, a pair of oppositely connected line closers, a group of switch pairs, said group having one contact of one switch of each pair in circuit with one of said pair of lines and the other contacts of said 85 switches alternately in circuit with one each of said pair of line closers, and said group having one contact of one switch of each of the other pairs connected in twos alternately with one or the other of said pair of lines and said resistance line, and the other to 90 said oppositely connected line closer, means for actuating said line closer and means for actuating the switch pairs in selection to 95 send to line successive plural characteristic impulses.

100 105 2. In a selective system a north and south line, a source of electrical energy for said lines, a pair of lines connected to opposite terminals of said source of energy, a third line from said source of energy, a resistance in said third line, three pairs of oppositely connected line closers, three groups of switch pairs, each of said groups having one contact of one switch of each pair in circuit with one of said pair of lines and the other contact of said switches alternately in circuit with one or the other of said pairs of line closers, and each of said groups having one contact of one switch of each of the other pairs connected in twos alternately with either one or the other of said pair of lines and said resistance line, and the other of said switches to said oppositely connected line closers alternately, means for 110 successively actuating said line closers and 115 means for actuating one switch pair of one or more groups in characteristic selection to 120 send to line successive plural characteristic impulses.

125 130 3. In a selective system a north and south

- line, a source of electrical energy for said lines, a pair of lines connected to opposite terminals of said source of energy, a third line from said source of energy, a resistance in said third line, three pairs of oppositely connected line closers, three groups of switch pairs, means for successively actuating said line closers and means for actuating one switch pair of one or more groups in 5 characteristic selection to send to line successive plural characteristic impulses.
4. In a selective system, a line, a source of electrical energy, a resistance, a plurality of oppositely connected line closers connected in pairs, a plurality of groups of switches, means for actuating one switch of one or more groups to connect said source of energy either directly or through said resistance and means for successively actuating said 10 line closers in pairs to send to line successive plural characteristic impulses.
5. In a selective system, a line, a source of electrical energy for said line, a resistance, two conductors connected respectively to the 15 positive and negative terminals of said source, a third conductor connected to said resistance and to one of said terminals of said source, a plurality of switches having switch elements connected to each of said conductors and arranged in pairs and adapted as one or more pairs to be selectively closed by a plurality of keys, a plurality of interconnected line closers and connected in pairs to said pairs of switches, the 20 extreme terminals of said line closers being connected to said line, and means for actuating said line closers in pairs in succession.
6. In a selective system, a line, a source of 25 electrical energy for said line, a pair of lines connected to different terminals of said source of energy, a third line from said source of energy, a resistance in said third line, a plurality of oppositely connected 30 pairs of line closers, a plurality of groups of pairs of switches, each of said groups having one contact of one switch of each pair in circuit with one of said pair of lines and the other contact of said switches in 35 circuit with one of said oppositely connected line closers, and each of said groups having one contact of one switch of each of the other pairs connected with either one or the other of said pair of lines and said resistance line, and the other switch of each of the other pairs connected with the other of said oppositely connected line closers, means for successively actuating said line closers and means for actuating one switch pair of 40 one or more groups in characteristic selection to send to line successive plural characteristic impulses.
7. In a selective system, a line, a source of 45 electrical energy for said line, a resistance, two conductors connected respectively to the 50 positive and negative terminals of said source, a third conductor connected to said resistance and to one of said terminals of said source, a plurality of line closers divided into two groups, said groups being respectively connected to said north line and said south line, a plurality of switch pairs arranged in three groups, each group being connected to two of said line closers, means for selectively closing said 55 switch pairs, and means for successively actuating said line closers in pairs.
8. In a selective system, a line, a source of 60 electrical energy, two conductors connected respectively to the two terminals of said source, a third conductor connected through said resistance to one of said terminals, and a plurality of switches arranged in pairs connected alternatively in 65 two with said three conductors, a plurality of line closers connected in pairs to said pairs of line switches, said line closers being interconnected with each other and with said line, and means for closing said line closers successively in pairs.
9. In a selective system, a north and south line, a source of electrical energy, two conductors connected to two terminals of said source, a resistance, a third conductor connected through said resistance to one of said terminals of said source, a plurality of line closers divided into two groups, said groups being respectively connected to said north line and said south line, a plurality of switch pairs arranged in three groups, each group being connected to two of said line closers, means for selectively closing said switch pairs, and means for successively actuating said line closers in pairs.
10. A selective system comprising a north line and a south line, means for producing electrical currents of different strength and polarity, means for systematically selecting said currents, and means for successively sending to said north line and said south line a plurality of said selected currents, said latter means including six line closers connected as two groups, said groups being connected respectively to said north line and said south line.
11. A selective transmitting system comprising means for producing electrical currents of different strength and polarity, a plurality of switches arranged in pairs, means for connecting said switches to said means and for operating said switches to secure currents of different strength and polarity, a line, a plurality of line closers connected to said line and connected in pairs to said pairs of switches, and means for actuating said line closers successively in pairs.
12. A selective transmitting system comprising means for producing electrical currents of different strength and polarity, twelve switch pairs arranged in three groups and adapted to be selectively closed upon operation of the keys of the typewriter, six

line closers, and connected in three groups to said three groups of switch pairs, a north line connected to three of said line closers, a south line connected to the remaining three 5 of said line closers, and means for successively actuating said line closers in pairs.

13. A selective transmitting system comprising means for producing electrical currents of different strength and polarity, 10 twelve switch pairs arranged in three groups and adapted to be selectively closed upon operation of the keys of the typewriter, six line closers, and connected in three groups to said three groups of switch pairs, a north 15 line connected to three of said line closers, a south line connected to the remaining three of said line closers, and means for continuously actuating said line closers successively in pairs.
14. In a selective system, a source of electrical energy for said line, a resistance, a plurality of line closers for sending to line multiple impulses of either polarity, a shaft, a plurality of cams set at different phases 25 thereon to successively actuate said closers, a plurality of groups of means for connecting said closers with said source of energy either direct or through said resistance, and operating means for selecting two or more 30 of said connecting means.

15. In a system, a line, a source of electrical energy for said line, a pair of lines connected to different terminals of said source of energy, a third line connected to 35 one terminal of said source of energy, a resistance in said third line, three pairs of oppositely connected line closers, three groups of switch pairs, each of said groups having one contact of one switch of each 40 pair in circuit with one of said oppositely phased lines and the other contacts of said switch alternately in circuit with one or the other of said pairs of line closers and each of said groups having one contact of one

switch of each of the other pairs connected 45 alternately with either one or the other of said oppositely phased lines and said resistance line and the other of said switches to said oppositely connected line closers alternately, means for successively actuating said 50 line closers and means for actuating one switch pair of one or more groups in characteristic selection to send to line successive plural characteristic impulses.

16. A transmitting system comprising 55 means for producing currents of different polarity and strength, a north line and a south line, and means for selectively sending impulses of different polarity alternately in succession along said north line and said 60 south line, said means comprising a plurality of switches arranged in groups, a plurality of groups of line closers connected to said north line and said south line, and means for actuating the line closers connected to one of said lines and the line closers connected to the other of said lines 65 at different instants.

17. A transmitting system comprising a line, means for producing currents of different polarity and strength, three leads 70 running from said means, a plurality of groups of switch pairs, the elements of the switch pairs of each group being connected alternately in twos to said three leads, a 75 plurality of sets of line closers connected to said line, the line closers of each set being connected in series with each other, said sets or line closers being divided into groups connected respectively to said groups of switch 80 pairs, and means for actuating said line closers successively in groups.

In testimony whereof, I affix my signature in presence of two witnesses.

ELMER A. BURLINGAME.
